UNITED STATES PATENT OFFICE.

JOSEPH WEASLER, OF CASCADE, WISCONSIN.

BABY-CARRIAGE.

1,385,959.

Specification of Letters Patent. Patented July 26, 1921.

Application filed July 15, 1919, Serial No. 310,953. Renewed April 20, 1921. Serial No. 463,078.

To all whom it may concern:

Be it known that I, JOSEPH WEASLER, a citizen of the United States, residing at Cascade, in the county of Sheboygan, State of Wisconsin, have invented certain new and useful Improvements in Baby-Carriages; and I do hereby declare the following to be a full, clear, and exact description of the invention, such as will enable others skilled in the art to which it appertains to make and use the same.

This invention is an improvement in motor vehicles and has particular reference to a reciprocating mechanism for baby carriages.

An object of the invention is to provide improved means for imparting a reciprocating movement to the vehicle, said means having portions thereof adjustable in order to regulate the length of such movement.

Another object is to render inactive the means for reciprocating the vehicle when it is desired to propel the latter from one place to another.

A further object is the provision of a mechanism for decreasing the speed of the vehicle as the same approaches the ends of its reciprocating movements in order that the direction of travel be reversed without undue jerking.

A still further object is the provision of a mechanism of the character specified which is simple in construction, easy to manufacture and effective in carrying out the purpose for which it is designed.

The inventive idea involved is capable of receiving a variety of mechanical expressions, one of which, for the purpose of illustrating the invention, is shown in the accompanying drawing wherein:

Figure 1 is a side elevation of a baby carriage constructed in accordance with the invention.

Fig. 2 is a top plan view with the body of the carriage removed and the casing of the mechanism shown in section.

Fig. 3 is a longitudinal section on the line 3-3 of Fig. 2 looking in the direction of the arrow.

Fig. 4 is a similar view on the same line looking in the opposite direction.

Fig. 5 is a transverse section on the line 5-5 of Fig. 2.

Fig. 6 is a section on the line 6-6 of Fig. 2.

Fig. 7 is a fragmentary detailed perspec-

tive view of the means for lifting the reciprocating element.

Fig. 8 is a detailed perspective view of the means for regulating the length of movement of the reciprocating element.

In the drawings, the numeral 10 indicates the body of a baby carriage which may be of any desired construction and which is provided with the front and rear axles 11 and 12, respectively, upon which are mounted the wheels 13 in the usual manner.

A rectangular casing 14 is preferably supported in a desired manner beneath the body 10 and is employed for inclosing the mechanism for reciprocating the carriage or vehicle.

A frame is mounted within the casing 14 and preferably includes the longitudinal bars or members 15 and the end bars or members 16. Preferably mounted in suitable bearings 17 carried by the bars 15

adjacent the rear ends thereof is a transverse drive shaft 18 upon which is mounted a motor casing 19 having a spring 20 therein one end of which is secured to the shaft so

that when the spring is unwinding the same will operate to rotate the shaft 18 in the desired direction. One end of the shaft 18 projects through the casing 14 and is provided upon the exterior end thereof with a crank handle 21 used to wind the spring 20 after the same has been unwound. Since the construction of this spring motor may be of any desired type a further detailed description thereof is deemed unnecessary.

A train of gearing is employed for transmitting the rotation of the shaft 18 to the front axle 11 of the vehicle and preferably comprises a large gear 22 mounted upon the shaft 18 between the bars 15 and meshing with a small gear 23 keyed to a shaft 24

supported upon the bars 15 in a parallel relation to the shaft 18. This shaft 24 also carries a large gear 25 which, in turn, meshes with a small gear 26 supported upon a third shaft 27 mounted in bearings upon the bars 15. The ends of the shaft 27 project beyond the sides of the bars 15 and have secured thereto the drive disks 28 and 29, the former having connected thereto a pitman rod 30 which is also pivotally secured to an oscillatory lever 31 the other end of which is connected by a link

32, to one end of a reciprocating rack bar 33 having the teeth 34 upon its under surface, said bar being slidable in a guide 35 carried by the adjacent bar 15. Preferably

carried by the front axle 11 is a small gear 36 which meshes with the teeth 34 so that when the rack bar 33 is reciprocated an oscillatory movement will be imparted to the gear 36 and consequently the axle 11 to move the vehicle back and forth. The pivot 37 of the lever 31 is vertically adjustable in a guide 38 carried by one of the bars 15 and said pivot is connected to one end of a bell-crank 39 which is operable to shift the position of said pivot. This adjustment is provided for the purpose of raising and lowering the position of the pitman 30 so as to adjust the same toward and away from a horizontal alined position with respect to the rack bar 33 whereby to vary the length of strokes of said bar and thus regulate the length of movement of the vehicle back and forth, it being understood that when the pitman 30 is in substantial horizontal alinement with the rack bar the latter will have its shorter length of movement. To adjust the bell crank 39, the other end thereof is connected to one end of a rod 40 which extends rearwardly of the casing and is connected at its rear end to an adjusting lever 41 pivoted to the rear transverse bar 16 and operable in a slot 42 in the rear end of the casing 14 and extending within reach of the operator so that the lever may be readily adjusted. A notched quadrant 42' has its ends secured to the rear of the casing 14 and is provided thereon with numbers or other suitable indicia to indicate the desired length of movement of the vehicle and the lever 41 is provided with a tooth 43 engageable with the notches of the quadrant 42' in order to retain the lever 41 in its adjusted position, it being understood that the said lever is of sufficient resiliency to permit of the tooth 43 being disengaged from a notch and moved over the quadrant to any desired position in order that the length of the movement of the vehicle may be changed.

It becomes desirable, at times, to propel the carriage or vehicle from one place to another and in order to accomplish this purpose it is necessary that the rack bar 33 be disengaged from the gear 36. To this end, a lifting lever 44 is provided upon one end with a pin 45 engageable in a slot 46 formed in the upper edge of the rack bar 33 so as to permit of a reciprocatory movement of said bar. The lever 44 is pivoted intermediate its ends at 47 and is connected at its other end to a bell-crank 48 which is in turn connected to a rod 49 extending rearwardly of the casing 14 and connected to an adjusting lever 50 mounted exteriorly of the casing and within reach of the operator so that by adjusting the lever 50 the lever 44 may be caused to raise the forward end of the rack bar and disengage the teeth 34 thereof from the gear 36 which will render the rack bar

inoperative and permit of the vehicle being constantly propelled in one direction.

It will be apparent from the description of the operation of the rack bar 33 that if the speed of the reciprocating movement thereof remained constant there would be a decided jerking of the vehicle at the ends of its movements which would negative the purpose of moving the vehicle back and forth and in order to overcome this jerking it is purposed to gradually decrease the speed of movement of the rack bar as the same approaches the ends of its strokes. In order that this purpose may be accomplished, a cushioning means is provided which preferably comprises an air cylinder 51 supported within the casing 14 and having air outlets 52 adjacent each end thereof which are controlled by means of valves 53 for the purpose of opening and closing said outlets. A piston rod 54 is slidably mounted in the cylinder 51 and has mounted thereon interiorly of the cylinder a piston 55 which will compress the air in the cylinder on either side of the piston as the same is reciprocated and owing to the small size of the outlets 52 it will be apparent that the column of air on either side of the piston will gradually retard the movement thereof as the same approaches either end of the cylinder and when the valve 53 is in opened position. The outer end of the piston rod 54 is connected to a pitman 56 which is in turn connected to the disk 29 so that as the latter rotates a reciprocating movement will be imparted to the piston rod. Owing to the variation in speed of the reciprocation of the piston 55 it will be apparent that the speed of rotation of the disk 29 and consequently the disk 28 and other parts connected thereto will also be varied accordingly. Means are provided for adjusting the valves 53 to open and close the outlets 52 and said means comprises a rod 57 connected, at one end, to the valve 53 and at its other end to an adjusting lever 58 pivotally mounted upon the casing 14. By closing the outlets 52 it will be obvious that the cylinder and piston can only be operated if at all by a considerable force being applied to the piston rod and in this manner an effective brake will be provided for the reciprocating mechanism.

A brake shoe 59 may also be utilized for positively preventing movement of the vehicle and this shoe is pivoted upon one of the bars 15 and engageable with the periphery of the disk 29 so as to prevent rotation thereof. The brake shoe is also connected, by a rod 60 to a lever 61 upon the rear of the casing 14 so that said shoe may be adjusted into and out of engagement with the disk 29.

What is claimed is:—

1. A wheeled vehicle having a frame and wheel supporting axles, a pinion carried by one of the axles, a bell crank pivotally con-

- nected with the frame, a rocker lever pivotally connected with the bell crank, a rack connected with the lever and engaging the pinion for imparting rotary movement to the pinion as the rack reciprocates, a rotary driving element, a pitman connecting the lever with the driving element and imparting operating movement to the lever as the driving element rotates, and means for rotating the driving element.
2. A wheeled vehicle having a frame and wheel supporting axles, a pinion carried by one of the axles, a slotted bracket carried by the frame, a rocker lever having a pivot extending through the slot of the bracket, a rack bar engaging the pinion and connected with one end of the lever, driving means connected with the opposite end portion of the lever for imparting operating movement to the lever, and means engaging the pivot of the lever for adjusting the position of the lever with respect to said bracket.
3. A wheeled vehicle having a frame and wheel supporting axles, a pinion carried by one of the axles, a rack engaging said pinion, means for imparting reciprocating move-
- ment to said rack, the rack having pivotal connection with its actuating means for movement into and out of engagement with the pinion, a pivotally mounted bell crank lever connected with the rack, and means for moving the bell crank lever to draw the rack out of engagement with the pinion.
4. A wheeled vehicle having a frame and wheel supporting axles, a pinion carried by one of the axles, a slidably mounted rack engaging the pinion, actuating means for the rack including a rotatably mounted driven shaft, and a brake structure comprising a cylinder, a piston slidably mounted in the cylinder and having a piston rod extending through one end of the cylinder, a disk carried by the shaft, and a pitman connecting the outer end portion of the piston rod with the disk.

In testimony whereof, I affix my signature, in the presence of two witnesses.
